WINDING DRUM FOR REELS

Fulton Rindge, Longmeadow, Mass.

Original application October 8, 1936, Serial No. 104,678. Divided and this application June 14, 1937, Serial No. 148,169

2 Claims. (Cl. 242—117)

This application is a division of my prior application Serial No. 104,678, filed by me October 8, 1936 on a Reel and relates to subject matter originally presented therein.

5 This invention relates to reels of the "dresser" type on which yarn is wound preparatory to warping, and relates more particularly to the winding drum or cylinder used in such a reel. In the operation of the dresser type of reel, threads or 10 yarns are brought to the reel from spools mounted in an adjacent creel and are secured to a section of the winding drum, which is then rotated to wind the threads or yarns on the drum. As the winding proceeds, the drum is fed slowly 15 axially relative to the threads or yarns, so that the latter form a yarn section on the reel.

It is desired that this yarn section be diamond-shape in cross section, and in order to attain this result, it has been customary to provide a winding member of slatted construction, having a plurality of spaced bars at one end of said member which could be adjusted at various angles to support the yarns and thus produce the desired diamond-shape section. Such constructions are 20 shown for instance in the prior patent to Thiel No. 934,580, and in the prior patent to Mallison No. 513,431.

It is the object of my present invention to provide in a reel a winding drum of improved construction, which preferably comprises a sheet 30 metal drum having an enlarged truncated conical portion at one end thereof and which is permanently assembled therewith. A further object of my invention is to provide improved means for securing the yarn ends to the drum.

35 My invention further relates to arrangements and combinations of parts which will be herein-after described and more particularly pointed out in the appended claims.

A preferred form of the invention is shown in 40 the drawings, in which

Fig. 1 is a sectional side elevation of a reel embodying my invention; and

Fig. 2 is an end view, looking in the direction of the arrow 2 in Fig. 1.

45 Referring to the drawings, I have shown my improved winding drum mounted in a reel comprising a frame having end members 10 and 11, connected by a plurality of upper and lower cross beams 12 and 13. The frame is mounted on rolls 50 15 having V-shaped grooves and supported on rails 16 and 17. Suitable provision is made for advancing the reel along the rails to provide transverse feed during the winding operation.

55 My improved winding drum comprises a cylind-

rical shell 22, preferably of sheet steel, mounted on flanged discs or supporting members 23 having hubs 24 secured to a main drive shaft 25. The shaft 25 is mounted in bearings 26 and 27 on brackets 28 and 29 secured respectively to the end members 10 and 11.

A gear 30 is mounted on the drive shaft 25 and secured to one of the flanged members 23, and is rotated by a pinion 31 which is mounted on a countershaft 32 and continuously rotated from 10 any suitable source of power. The supporting members or discs 23 are provided with annular brake flanges 35, positioned for engagement by 15 brake shoes 36 pivotally connected at 37 (Fig. 2) and forced outward against the brake flanges 35 by any suitable expanding means not shown herein.

The drum 22 is provided at one end with an annular conical portion 40 in the form of a hollow truncated sheet metal cone which is welded or otherwise permanently secured at its smaller 20 end to the outer surface of the drum 22, as indicated at 41 in Fig. 1, and which has its larger end portion secured in concentric relation to the drum 22 by a spacing ring 44. The ring 25 44 is mounted at the end of the cylinder or drum 22 and is preferably welded or otherwise permanently secured to the outer surface of the drum 22 and to the inner surface of the conical member 40.

I thus provide a drum having a continuous 30 cylindrical winding surface and having a permanently assembled conical end portion which is accurately concentric with the drum and which supports the yarn ends in such manner that successive sections A, B, C, D and E (Fig. 1) may be 35 wound thereon, each having the desired diamond-shape cross section.

In order that the yarn ends may be conveniently secured to the surface of the cylindrical drum, I provide the drum with a series of circular openings 50 (Fig. 1) each having circumferential extensions or recesses 51. The yarn ends to be attached to a particular portion of the drum are assembled in groups and tied in knots which are then passed through selected openings 50 45 but which are too large to be drawn through either recess 51. As the winding commences, the knots will be drawn into one or the other of the recesses 51 and will be firmly retained. By providing oppositely disposed recesses 51, the 50 yarn is firmly held, whether the drum is rotated clockwise or anti-clockwise.

The cylindrical sheet metal construction of my improved reel is a marked improvement over the slat construction previously common and shown 55

in said prior patents to Thiel and Mallison. The supporting members 23, being spaced well inward from the ends of the drum, not only satisfactorily support the drum but also permit parts of the operating mechanism to be mounted within the ends of the drum and to be effectively protected thereby. The permanently secured and rigid construction of the conical end portion 40 of the drum is also a substantial improvement over the 10 loosely connected and widely spaced adjustable bars previously in use.

Having thus described my invention and the advantages thereof, I do not wish to be limited to the details herein disclosed, otherwise than as 15 set forth in the claims, but what I claim is:

1. In a warping reel in which multi-thread sections of yarn are wound preparatory to warping, a yarn-receiving drum comprising a sheet metal cylinder and an enlarged truncated conical portion mounted on said cylinder adjacent one end

thereof, said conical portion being permanently secured to the outside of said cylinder at a point spaced from one end of said cylinder, said cylinder being provided with openings therethrough to receive the knotted ends of groups of warp yarns. 5

2. In a warping reel in which multi-thread sections of yarn are wound preparatory to warping, a yarn-receiving drum comprising a sheet metal cylinder, an enlarged truncated conical portion mounted on said cylinder adjacent one 10 end thereof, said conical portion being also of sheet metal and being permanently secured to the outside of said cylinder at a point spaced from one end of said cylinder, and an annular flanged ring interposed between and secured to said cylinder and the larger end of said conical portion and holding said parts in concentric spaced relation. 15

FULTON RINDGE. 20
